DIE PRESS WITH TRAVELING HEAD

Edgar Haas, New York, N.Y., assignor to Herman Schwabe, Inc., Brooklyn, N.Y., a corporation of New York

Filed Sept. 6, 1962, Ser. No. 221,703
18 Claims. (Cl. 83—534)

This invention relates to die presses and more particularly to die presses having a traveling head.

It is common to cut shaped pieces out of sheet material such as fabric, leather or plastics by means of a clicker press having a swinging head. Multiple plies are cut by manually placing one or more steel rule dies on the material, following which the press platen descends to make the cut. The material is supported on a table having a suitable cutting block. When the material comes in wide sheets, a different form of press has been devised having upright rods carrying an elongated bridge at the top and an elongated table beneath the bridge. A traveling head is carried by and is movable along the bridge for travel over the table. The traveling head has a cylinder and piston for operating a platen therebeneath.

The primary object of the present invention is to generally improve die presses of the traveling head type. A more particular object is to improve such presses by eliminating the need for flexible hydraulic piping leading to the traveling head. A further object is to provide a sturdy rigid machine which also facilitates adjustment of the height of the table. Still another object is to improve and simplify the electrical and hydraulic control elements of the press, for maximum convenience and speed in operating the same.

To accomplish the foregoing general objects and other more specific objects which will hereinafter appear, my invention resides in the traveling head press elements, and their relation one to another, as are hereinafter more particularly described in the following specification. The specification is accompanied by drawings in which:

FIG. 1 is a perspective view showing a traveling head press embodying features of the present invention;

FIG. 2 is a fragmentary horizontal section taken approximately in the plane of the line 2—2 of FIG. 5;

FIG. 3 is a partially sectioned end elevation of the press;

FIG. 4 is a fragmentary horizontal section taken approximately in the plane of the line 4—4 of FIG. 3;

FIG. 5 is a fragmentary vertical section showing the rack and pinion mechanism for causing travel of the head;

FIG. 6 is a schematic flow diagram showing the hydraulic circuit of the press; and

FIG. 7 is a wiring diagram showing the electrical circuit of the press.

Referring to the drawings, and more particularly to FIG. 1, the press comprises a sturdy frame having rigid upright ends 12 and 14 carrying an elongated bridge 16 at the top. There is an elongated table 18 between the ends 12 and 14. A traveling head, generally designated 20, is carried by and is movable along the bridge 16 for travel over the table 18.

Referring now to FIG. 6, the traveling head includes a cylinder 22 and a piston 24 having a piston rod 25 carrying a platen 26 therebeneath. The platen 26 is moved toward or away from a long cutting block (28 in FIG. 1) carried by the table 18. There is also a tank 30 for hydraulic fluid, and a pressure pump 32 receives fluid from the tank 30 and is driven by an electric motor 34. The pump 32 preferably is submerged in the hydraulic fluid, and the motor 34 preferably is disposed over the pump and tank. There is also a control valve 36 and pipes 38, 40, and 42 between the pump 32 and the cylinder 22.

der 22. In accordance with the present improvement, the tank 30, the pump 32, the motor 34, the valve 36, and the piping are all mounted on and form a part of the traveling head and move therewith.

Referring now to FIGS. 2 and 5, there is a stationary gear rack 44 extending along the bridge. A reversible hydraulic motor 46 is fixedly mounted on the head 20 and drives a pinion 48 meshing with the rack 44. A control valve 50 (FIG. 6) and pipes 52, 54, 56 and 58 are connected between a submerged pump 60 and the reversible hydraulic motor 46. As here illustrated, the valve 50 is controlled by movement to one side or the other of a handle 62, which handle preferably is self-centering. This handle is carried by the traveling head, as will be clear from FIGS. 1 and 3. A small movement of the handle to the left causes the head to travel to the left, and movement of the handle to the right causes the head to travel to the right.

In accordance with the present improvement, the tank 30 for the hydraulic fluid, the submerged pump 60, the electric motor 34, the reversible hydraulic motor 46, the valve 50 and the piping are all mounted on and form a part of the traveling head and move therewith.

With this arrangement there is no need for the usual flexible hydraulic piping between a stationary tank and pump and the traveling head. Instead the head is extended upward by means of supports 64 (FIGS. 1 and 3) located on both sides of the bridge 16, the said supports carrying a movable hydraulic tank 30 and electric motor 34 with the submerged pump operated thereby. With this arrangement the only flexible connection to the traveling head required is an electric supply wire. This is readily provided, and is not soon subject to mechanical fatigue and breakage as is the case with hollow flexible tubing subjected to high internal pressure.

It is frequently necessary to adjust the height of the table 18. This depends on the height of the die, the vertical travel of the platen, the wear of the cutting block 28, and other such factors. A precise adjustment is important so that, on the one hand the die will cut all the way through the material, including the lowermost layer of material, and on the other hand will not penetrate the block more than is needed to just cut through the lowermost layer of material.

In accordance with a feature of the present invention, there are four tie rods 70 (FIGS. 1, 3 and 4) depending from the bridge 16, these rods being held at their upper ends by nuts 72. The lower ends of the rods pass through and carry the ends of the table, and are threaded to receive internally threaded nuts which are beneath the table and which support the table against the cutting force. The nuts are turned by gears, and in fact constitute internally threaded gears, indicated at 74. There is additional gearing connecting the said internally threaded gears 74 for simultaneous equal rotation when adjusting the height of the table.

More specifically, referring to FIGS. 3 and 4, a manually operable crank 76 at one end of the press turns a rod 78 which is carried by and extends lengthwise beneath the table 18. The shaft 78 has a gear 80 at each end inside the frame of the machine and meshing with gearing 82 and 84 leading to the internally threaded gears 70. The gearing is all carried by and moves up and down with the table. The frame end 14 (FIG. 3) is cut away at 79 to permit up and down movement of shaft 79. In the present case the gears 84 are worm gears, but the table support system as a whole would anyway be irreversible because of the threaded tie rods 70, which are incapable of turning the internally threaded gears 74. The gears 84, 74 therefore could be helical gears, this representing merely a change in pitch.

A feature of the present machine is that the tie rods 70

are free at their lower ends, and act solely as suspension members to resist the cutting force of the press. They need not, as heretofore, constitute the guide means. The rigid cast frame ends 12 and 14 preferably have vertical guideways indicated at 86. Each guideway has two guide surfaces at right angles. These cooperate with the corners of the table 18 to hold the table securely against lateral movement. The corners of the table have wear-blocks of brass or other bearing metal. With this construction the guide function for holding the table against horizontal movement is separated from the table height-adjusting function of the rotatable threaded tie rods 70, thereby providing a machine which is rigid and sturdy, and improving the precision of vertical adjustment obtainable by means of the tie rods.

Considering the construction of the press in greater detail, and referring to FIG. 1, the frame ends 12 and 14 are rigidly spaced and supported by a bottom brace 90 as well as the bridge 16 previously referred to. The bridge 16 is channel-shaped in section, and the brace 90 is an inverted channel. Referring to FIG. 5, the sides 16 of the bridge are connected by a bottom 92 having a raised middle web and support 94 for the gear rack 44. The lower end of the hydraulic tank 30 is received between the sides 16 of the bridge, and the tank is supported by upright supports 64 which are outside the bridge sides 16. The bridge includes rails 96, and the traveling head 20 has wheels 98 which roll freely on the rail 96, thus carrying the weight of the head as it travels along the bridge. However, there is an accurately machined horizontal face 100 forming a part of the head 20, and this slides accurately beneath a mating horizontal face 102 at the bottom of the bridge. These surfaces are in supporting contact during the cutting stroke, that is, they take the reaction to the force of the hydraulic piston and cylinder.

The table 18 is in the form of an inverted channel, the hollow space within which receives the shaft 78 and associated gearing shown in FIG. 4, that is, the channel of table 18 straddles the shaft and gearing which afford vertical adjustment of the table height.

The hydraulic circuit is shown in FIG. 6. A single pump 32 might be used to operate both the piston 24 and the travel motor 46, but it is here preferred to provide two pumps, a main high pressure pump 32 to operate the piston 24, and an auxiliary pump 60 to operate the travel motor 46. This auxiliary pump also operates pilot mechanism 37 for the four-way valve 36 controlling the piston 24. This valve has a self-centering spool.

A lower pressure is adequate for the travel motor 46, and for the pilot mechanism 37, than is needed for the main ram action for the platen 26. In the illustrated machine the pump 32 operates at 2000 pounds per square inch pressure, and the pump 60 operates at 600 pounds per square inch pressure. This lower pressure fluid is readily controlled by a four-way valve 50 which is manually operable by means of the handle 62. The platen movement is controlled electrically by means of a trigger 63 on handle 62, and by means of upper and lower limit switches. The electric circuit controls solenoids for the pilot 37 of main valve 36, and this is feasible while using solenoids of moderate size, whereas direct solenoid operation of the main four-way valve 36 would require very large solenoids and high electrical current.

The intake for pumps 32 and 60 is filtered at 104. The discharge from pump 60 flows through pipes 52 and 54 to the four-way valve 50, which is connected by a pipe 56 to drive the reversible motor 46 in one direction, and by a pipe 58 to drive the motor 46 in opposite direction. The return flow is through pipe 106 back to the tank 30. The handle 62 is self-centering, that is, it will not stay in either side position unless held there.

Referring now to FIG. 1, there are rods 108 and 110 projecting horizontally from the traveling head. These

are connected to the handle 62, and the arrangement is such that the rods 108 and 110 act as limit switches to limit the travel of the head 20. When the head reaches the left end of the press the rod 108 moves the handle away from its left position, and the head stops. At the other end the rod 110 strikes the end of the press and moves the handle 62 away from its right-hand position, and the head stops.

Between these extremes the head is readily moved back and forth by the operator who moves the handle left or right as desired. After placing one or more dies on the material and moving the platen back over the dies, the trigger 63 (FIG. 3) is touched, and this causes immediate descent of the platen for the desired cutting stroke.

Once the trigger has been pressed the platen goes through its full cycle, that is, it descends to bottom position, and then rises to top position, and then stops, regardless of whether the trigger is held or released.

In FIG. 1 attention is called to the push button 112. This is a safety button which is connected in series with the trigger, and which must be pressed by the operator's left hand at the same time that he squeezes the trigger 63 with his right hand. This insures that both hands are out of the press when the platen descends.

The buttons 114 and 116 are "start" and "stop" buttons for the motor 34 which drives the pumps. The "start" button controls a conventional magnetic starting switch at the motor, which may be a three-phase motor. Only a single flexible electric cable leading to the traveling head is needed, all switching being performed on the traveling head itself. The hydraulic piping may be and preferably is rigid piping instead of flexible tubing, there being no relative movement between the parts which are piped together. In FIG. 3 the parts 106 and 108 are bottom and top limit switches which are operated by a part 110 connected to the platen 26 for movement therewith. Referring to FIG. 6, the platen is carried by a large guide cylinder 27 (say twelve inch diameter) within which is housed a smaller operating cylinder 22 (say five inch diameter).

The electrical circuitry is shown in FIG. 7. Two possibilities may be described. In one case the operator presses the trigger (and/or safety button) only momentarily. In the other case the operator holds the trigger and safety button during the entire cycle.

In the first case the operator depresses both hand switches 63 and 112 to complete a circuit from line L2 through the hand switches, the normally closed contact R2-1 of relay R2, and then through the relay coil R1 to line L1.

The completion of this circuit energizes relay coil R1 and relay coil R3 which is in parallel with coil R1. The normally open contacts R1-1 and R1-2 of relay R1 close, and the normally closed contacts R3-1 of relay R3 open.

The closing of the contacts R1-1 energizes the "Down" solenoid coil 102 which causes pilot fluid to shift the spool of the hydraulic four-way valve (36 in FIG. 6), causing a flow of oil into the upper or pressure end of the hydraulic ram, moving it downward. At the same time, the opening of the R3-1 contacts keeps the "Up" solenoid coil 104 de-energized.

The closing of the R1-2 contacts serves as a holding contact which keeps relay coils R1 and R3 energized, even though the operator has removed his hands (or either hand) from the hand switches.

The hydraulic ram in its downward movement reaches the bottom limit switch (106 in FIG. 3) opening its normally closed contacts 106-1 (FIG. 7) and closing its normally open contacts 106-2. (The closing of the normally open contacts 106-2 and the consequent energizing of the relay coil R2 plays no part in this operation when the hand switches are released before the ram hits the bottom limit switch.)

The opening of the normally closed contacts 106-1

of the bottom limit switch de-energizes relay coils R1 and R3, which in turn opens relay contacts R1-1 and R1-2 and closes relay contacts R3-1. This in turn de-energizes the "Down" solenoid coil 102, and energizes the "Up" solenoid coil 104, causing the spool of the four-way valve to shift to allow oil to flow into the bottom of the hydraulic ram. The oil from the pressure or top end of the ram is exhausted through the four-way valve back to the oil tank.

As the hydraulic ram rises to its uppermost position it touches the top limit switch, opening its normally closed contacts 108-1. This in turn de-energizes the "Up" solenoid coil 104. With both solenoid coils de-energized, the spring-centered spool of the four-way valve returns to the neutral or middle position. Both cylinder ports then are blocked, and the oil flows from the pressure port to the exhaust port and back to the oil tank, that is, the oil simply circulates.

When the operator keeps both hand switches depressed during the entire cycle, the operation proceeds as described above until the ram reaches bottom, that is, the circuit closed by the hand switches energizes relay coil R1 and relay coil R3 so that the normally open contacts R1-1 and R1-2 close, and the normally closed contacts R3-1 open. This energizes the "Down" solenoid 102, causing the platen to move down.

When the hydraulic ram strikes the bottom limit switch, the opening of its normally closed contacts 106-1 does not de-energize relay coils R1 and R3. This is due to the fact that a completed circuit exists through the closed hand switches 63 and 112, and the normally closed contacts R2-1, relay coils R1 and R3, and back to line L1. The closing of the normally open contacts 106-2 by the bottom limit switch energizes relay coil R2, opening its normally closed contacts R2-1 and closing its normally open contacts R2-2. The opening of the normally closed contacts 106-1 of the bottom limit switch de-energizes relay coils R1 and R3, and a sequence of operations follows as described above, that is, the relay contacts R1-1 and R1-2 open, and the contacts R3-1 close. This de-energizes the "Down" solenoid 102 and energizes the "Up" solenoid 104, thereby raising the platen.

As the hydraulic ram rises and releases the bottom limit switch, relay coil R2 is kept in an energized condition through its own normally open holding contacts R2-2, which are now live because the hand switches are still depressed by the operator. The ram will return to its "Up" position to complete the cycle (unless the operator both releases and also again depresses both of the hand switches, which amounts to initiating another whole cutting cycle).

When the platen is fully up the normally closed contacts 108-1 of the top limit switch are opened, thereby de-energizing the "Up" solenoid 108. When both solenoids are de-energized, the spool of the four-way valve returns to midposition, and the platen remains stationary in its raised position. The oil from the pumps simply circulates.

In the above description the adjustment of the table height has been described as manually operated. However, I have made this machine with an electrically operated motor drive which is applied to the shaft 78 in lieu of the crank 76. The motor with its reduction gearing moves up and down with shaft 78 and the table.

It may be mentioned that the electrical equipment, including the relays shown in FIG. 7, and the motor starter, are housed in a box located at the broken line rectangle shown at 31 in FIG. 6.

It is believed that the construction and operation of my improved die press with traveling head, as well as the advantages thereof, will be apparent from the foregoing detailed description. It will also be apparent that while I have shown and described the invention in a preferred form, changes may be made without departing from the scope of the invention as sought to be defined in the fol-

lowing claims. In the claims the reference to a crank is not intended to exclude an equivalent hand wheel.

I claim:

1. A die press of the traveling head type for cutting sheet material by means of freely movable dies, said press comprising a frame having upright ends carrying an elongated bridge at the top, an elongated table between the ends beneath the bridge, a traveling head carried by and movable along the bridge for travel over the table, a cylinder and piston in said head and disposed for reaction against the bottom of the bridge, a platen therebeneath moved toward or away from the table by the cylinder and piston, a tank for hydraulic fluid, a pressure pump receiving fluid from the tank, a motor to drive said pump, a control valve and piping between the pump and the cylinder, said tank, pump, motor, valve and piping all being mounted on and forming a part of the traveling head for movement therewith.
2. A die press of the traveling head type for cutting sheet material by means of freely movable dies, said press comprising a frame having upright ends carrying an elongated bridge at the top, an elongated table between the ends beneath the bridge, a traveling head carried by and movable along the bridge for travel over the table, a cylinder and piston in said head and disposed for reaction against the bottom of the bridge, a platen therebeneath moved toward or away from the table by the cylinder and piston, a tank for hydraulic fluid, a pressure pump submerged in the fluid in the tank, a motor over the tank and having a vertical shaft to drive said pump, a control valve and piping between the pump and the cylinder, said tank, pump, motor, valve and piping all being mounted on and forming a part of the traveling head for movement therewith.
3. A die press of the traveling head type for cutting sheet material by means of freely movable dies, said press comprising a frame having upright ends carrying an elongated bridge at the top comprising relatively deep spaced-apart side walls having tracks formed on the exterior near the bottom, an elongated table between the ends beneath the bridge, a traveling head having wheels carried by and movable along the tracks of the bridge for travel over the table, a platen therebeneath moved toward or away from the table, a tank for hydraulic fluid, the lower part of said tank being received between the side walls of the bridge, a pressure pump submerged in the fluid in the tank, a motor over the tank and having a vertical shaft to drive said pump, a gear rack extending along said bridge, a reversible hydraulic motor mounted on said head driving a pinion meshing with said rack, a control valve and piping between the pump and said reversible hydraulic motor, said tank, pump, motors, valve, and piping all being mounted on and forming a part of the traveling head for movement therewith.
4. A die press of the traveling head type for cutting sheet material by means of freely movable dies, said press comprising a frame having upright ends carrying an elongated bridge at the top, an elongated table between the ends beneath the bridge, a traveling head carried by and movable along the bridge for travel over the table, a cylinder and piston in said head and disposed for reaction against the bottom of the bridge, a platen therebeneath moved toward or away from the table by the cylinder and piston, a tank for hydraulic fluid, a pressure pump receiving fluid from the tank, a motor to drive said pump, a control valve and piping between the pump and the cylinder, a reversible hydraulic motor mounted on said head for causing travel of the head along the bridge, a second control valve and piping between the pump and said reversible hydraulic motor, said tank, pump, motors, valves, and piping all being mounted on and forming a part of the traveling head for movement therewith.
5. A die press of the traveling head type for cutting sheet material by means of freely movable dies, said press comprising a frame having upright ends carrying an elongated bridge at the top, an elongated table between the ends beneath the bridge, a traveling head carried by and movable along the bridge for travel over the table, a cylinder and piston in said head and disposed for reaction against the bottom of the bridge, a platen therebeneath moved toward or away from the table by the cylinder and piston, a tank for hydraulic fluid, a pressure pump submerged in the fluid in the tank, a motor over the tank and having a vertical shaft to drive said pump, a gear rack extending along said bridge, a reversible hydraulic motor mounted on said head driving a pinion meshing with said rack, a control valve and piping between the pump and said reversible hydraulic motor, said tank, pump, motors, valve, and piping all being mounted on and forming a part of the traveling head for movement therewith.

6. A die press of the traveling head type for cutting sheet material by means of freely movable dies, said press comprising a frame having upright ends carrying an elongated bridge at the top comprising relatively deep spaced-apart side walls having tracks formed on the exterior near the bottom, an elongated table between the ends beneath the bridge, a traveling head having wheels carried by and movable along the tracks of the bridge for travel over the table, a platen therebeneath moved toward or away from the table, a tank for hydraulic fluid, the lower part of said tank being received between the side walls of the bridge, a pressure pump submerged in the fluid in the tank, a motor over the tank and having a vertical shaft to drive said pump, a gear rack extending along said bridge, a reversible hydraulic motor mounted on said head driving a pinion meshing with said rack, a control valve and piping between the pump and said reversible hydraulic motor, said tank, pump, motors, valve, and piping all being mounted on and forming a part of the traveling head for movement therewith.

gated bridge at the top, an elongated table between the ends beneath the bridge, a traveling head carried by and movable along the bridge for travel over the table, a cylinder and piston in said head and disposed for reaction against the bottom of the bridge, a platen therebeneath moved toward or away from the table by the cylinder and piston, a tank for hydraulic fluid, a pressure pump submerged in the fluid in the tank, a motor over the tank and having a vertical shaft to drive said pump, a control valve and piping between the pump and the cylinder, a gear rack extending along said bridge, a reversible motor mounted on said head driving a pinion meshing with said rack, a second control valve and piping between the pump and said motor, said tank, pump, motors, valves, and piping all being mounted on and forming a part of the traveling head for movement therewith.

6. A die press comprising a frame having upright ends carrying an elongated bridge at the top, a table between said ends beneath the bridge, a cylinder and piston carried by said bridge, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, nuts on said threaded rods beneath the table to support the table at a desired height, and gearing for simultaneous equal rotation of said nuts when adjusting the height of the table.

7. A die press comprising a frame having upright ends carrying an elongated bridge at the top, a table between said ends beneath the bridge, a cylinder and piston carried by said bridge, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, and nuts on said threaded rods beneath the table to support the table at a desired height, said frame ends having vertical guideways cooperating with the ends of the table to hold the table against lateral movement.

8. A die press comprising a frame having upright ends carrying an elongated bridge at the top, a table between said ends beneath the bridge, a cylinder and piston carried by said bridge, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, nuts on said threaded rods beneath the table to support the table at a desired height, and gearing for simultaneous equal rotation of said nuts when adjusting the height of the table, said frame ends having vertical guideways cooperating with the ends of the table to hold the table against lateral movement.

9. A die press comprising a frame having upright ends carrying an elongated bridge at the top, a table between said ends beneath the bridge, a traveling head carried by and movable along the bridge for travel over the table, a cylinder and piston in said head, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, nuts on said threaded rods beneath the table to support the table at a desired height, and gearing for simultaneous equal rotation of said nuts when adjusting the height of the table.

10. A die press comprising a frame having upright ends carrying an elongated bridge at the top, a table between said ends beneath the bridge, a traveling head carried by and movable along the bridge for travel over the table, a cylinder and piston in said head, a platen therebeneath and

5 moved toward or away from the table by the cylinder and piston, tie rods depending from said bridge within said frame ends, said table being suspended from said bridge by means of said tie rods, the lower portion of said rods passing through the ends of said table and being threaded, nuts on said threaded rods beneath the table to support the table at a desired height, said frame ends having vertical guideways cooperating with the ends of the table to hold the table against lateral movement.

11. A die press comprising a frame having upright ends carrying an elongated bridge at the top, a table between said ends beneath the bridge, a traveling head carried by and movable along the bridge for travel over the table, a cylinder and piston in said head, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, nuts on said threaded rods beneath the table to support the table at a desired height, and gearing for simultaneous equal rotation of said nuts when adjusting the height of the table, said frame ends having vertical guideways cooperating with the ends of the table to hold the table against lateral movement.

12. A die press comprising a frame having upright ends carrying an elongated bridge at the top, a table between said ends beneath the bridge, a traveling head carried by and movable along the bridge for travel over the table, a cylinder and piston in said head, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, internally threaded gears on said threaded rods beneath the table to support the table at a desired height, and means including gearing connecting said threaded gears for simultaneous equal rotation when adjusting the height of the table, said frame ends having vertical guideways cooperating with the ends of the table to hold the table against lateral movement, the aforesaid gearing including a shaft extending lengthwise beneath the table and having a gear at each end meshing with the gearing leading to the aforesaid threaded gears.

13. A die press comprising a frame having upright ends carrying an elongated bridge at the top, a table between said ends beneath the bridge, a traveling head carried by and movable along the bridge for travel over the table, a cylinder and piston in said head, a platen therebeneath and moved toward or away from the table by the cylinder and piston, tie rods depending from said bridge within said frame ends, said table being suspended from said bridge by means of said tie rods, the lower portion of said rods passing through the ends of said table and being threaded, internally threaded gears on said threaded rods beneath the table to support the table at a desired height, and manually operable means including gearing connecting said threaded gears for simultaneous equal rotation when adjusting the height of the table, said frame ends having vertical guideways cooperating with the ends of the table to hold the table against lateral movement, the aforesaid gearing including a crank operated shaft extending lengthwise beneath the table and having a crank at one end outside the frame and having a gear at each end inside the frame meshing with the gearing leading to the aforesaid threaded gears, the frame end being vertically slotted to accommodate any resulting movement of the crank operated shaft.

14. A die press comprising a frame having upright ends carrying an elongated bridge at the top, said bridge comprising relatively deep spaced-apart side walls having tracks, an elongated table between the upright ends beneath the bridge, a traveling head carried by and movable along the bridge for travel over the table, said head in-

cluding a cylinder and piston with a platen therebeneath moved toward or away from the table by the cylinder and piston, the top of said cylinder being slideable along the bottom of the bridge for reaction thereagainst, rollers on said head resting on said tracks to support the head for rolling movement along the bridge, a tank on said head for hydraulic fluid, said tank being disposed between the side walls of the bridge, a pressure pump submerged in the fluid in the tank, an electric motor over the tank having a vertical shaft extending down to said pump, a control valve and piping between the pump and the cylinder, said tank, pump, motor, valve and piping all being mounted on and forming a part of the traveling head for movement therewith.

15. A die press comprising a frame having upright ends carrying an elongated bridge at the top, said bridge comprising relatively deep spaced-apart side walls, said side walls having tracks formed on the exterior near the bottom thereof, an elongated table between the upright ends beneath the bridge, a traveling head carried by and movable along the bridge for travel over the table, said head including a cylinder and piston with a platen therebeneath moved toward or away from the table by the cylinder and piston, the top of said cylinder being slideable along the bottom of the bridge for reaction thereagainst and having upstanding arms which straddle the bridge, rollers on said arms resting on said tracks to support the head for rolling movement along the bridge, a tank for hydraulic fluid, said tank having its lower end disposed between the side walls of the bridge, its upper end being exposed above the bridge and being wider than the bridge, said tank being supported at its enlarged upper end by the aforesaid upstanding arms of the head, a pressure pump submerged in the fluid in the tank, an electric motor over the tank having a vertical shaft extending down to said pump, a control valve and piping between the pump and the cylinder, said tank, pump, motor, valve, and piping all being mounted on and forming a part of the traveling head for movement therewith.

16. A die press comprising a frame having upright ends carrying an elongated bridge at the top, said bridge comprising relatively deep spaced-apart side walls, said side walls having tracks formed near the bottom thereof, a gear rack along said bridge, an elongated table between the upright ends beneath the bridge, a traveling head carried by and movable along the bridge for travel over the table, said head including a cylinder and piston with a platen therebeneath moved toward or away from the table by the cylinder and piston, the top of said cylinder being slideable along the bottom of the bridge for reaction thereagainst and having upstanding arms which straddle the bridge, rollers resting on said tracks to support the head for movement along the bridge, a tank for hydraulic fluid, said tank being exposed above the bridge and being wider than the bridge, said tank being supported at its upper end by the aforesaid upstanding arms of the head, a pressure pump, an electric motor for driving said pump, a control valve and piping between the pump and the cylinder, a reversible hydraulic motor mounted on said head and driving a pinion meshing with said rack, a second control valve and piping between the pump and said hydraulic motor, said tank, pump, motors, valves, and piping all being mounted on and forming a part of the traveling head for movement therewith.

17. A die press comprising a frame having upright ends carrying an elongated bridge at the top, said bridge comprising relatively deep spaced-apart side walls, said side

walls having tracks formed on the exterior near the bottom thereof, a gear rack along said bridge, an elongated table between the upright ends beneath the bridge, a traveling head carried by and movable along the bridge for travel over the table, said head including a cylinder and piston with a platen therebeneath moved toward or away from the table by the cylinder and piston, the top of said cylinder being slideable along the bottom of the bridge for reaction thereagainst and having upstanding arms which straddle the bridge, rollers on said arms resting on said tracks to support the head for rolling movement along the bridge, a tank for hydraulic fluid, said tank having its lower end disposed between the side walls of the bridge, its upper end being exposed above the bridge and being wider than the bridge, said tank being supported at its enlarged upper end by the aforesaid upstanding arms of the head, a pressure pump submerged in the fluid in the tank, an electric motor over the tank having a vertical shaft extending down to said pump, a control valve and piping between the pump and the cylinder, a reversible hydraulic motor mounted on said head and driving a pinion meshing with said rack, a second control valve and piping between the pump and said hydraulic motor, said tank, pump, motors, valves, and piping all being mounted on and forming a part of the traveling head for movement therewith.

18. A die press comprising a frame having upright ends carrying an elongated bridge at the top, said bridge being channel-shaped and comprising relatively deep spaced-apart side walls connected by a bottom wall, said side walls having tracks formed on the exterior near the bottom thereof, a gear rack inside said channel near the bottom thereof, an elongated table between the upright ends beneath the bridge, a traveling head carried by and movable along the bridge for travel over the table, said head including a cylinder and piston with a platen therebeneath moved toward or away from the table by the cylinder and piston, the top of said cylinder being slideable along the bottom of the bridge for reaction thereagainst and having upstanding arms which straddle the bridge, rollers on said arms resting on said tracks to support the head for rolling movement along the bridge, a tank for hydraulic fluid, said tank being downwardly convergent and having its lower end disposed between the side walls of the bridge, its upper end being exposed above the bridge and being wider than the bridge, said tank being supported at its enlarged upper end by the aforesaid upstanding arms of the head, a pressure pump submerged in the fluid in the tank, an electric motor over the tank having a vertical shaft extending down to said pump, a control valve and piping between the pump and the cylinder, a reversible hydraulic motor mounted on said head within the bridge and driving a pinion meshing with said rack, a second control valve and piping between the pump and said hydraulic motor, said tank, pump, motors, valves, and piping all being mounted on and forming a part of the traveling head for movement therewith.
